UNITED STATES PATENT OFFICE.

WILLIAM ANDERSON, OF HELENSBURGH, JAMES MEIKLE, OF GLASGOW, AND CHARLES WILLIAM FULTON, OF PAISLEY, SCOTLAND.

FURNACE.

1,085,001.

Specification of Letters Patent.

Patented Jan. 20, 1914.

Application filed April 28, 1913. Serial No. 764,194.

To all whom it may concern:

Be it known that we, WILLIAM ANDERSON, JAMES MEIKLE, and CHARLES WILLIAM FULTON, subjects of the King of the United Kingdom of Great Britain and Ireland, and residing, respectively, at Helensburgh, Scotland; Glasgow, Scotland, and Paisley, Scotland, have invented a certain new and useful Improvement in Furnaces, of which the following is a specification.

This invention relates to furnaces, especially furnaces for steam generators, *e. g.*, furnaces for generators of the type having one or more flues, as described in the specification of our co-pending application filed Aug. 12, 1912, No. 714613.

The invention consists in a new construction of conveying means for removing ash.

In the accompanying drawings Figure 1 is a part elevation, part longitudinal section; Fig. 2 is a cross section showing a furnace of the type referred to fitted with a conveyer embodying the invention.

Referring to the drawings, the fuel support comprises a substantially V-shaped grate composed of two series of oppositely inclined bars A for supporting the fuel and merging at the lower edges of the V into the sides of an ash-receiving channel or trough B which is open on top and closed at the bottom and which is disposed longitudinally of the flue B¹ of a steam generator. Within said trough or channel B is fitted a helical conveyer C for removing ashes, which is interrupted at several points along its length, the depth and pitch of the thread being uniform, the length of the flights of the screw threads increasing progressively toward the front of the furnace and the interruptions being of unequal extent, decreasing toward the front of the furnace, so that the capacity of the conveyer increases progressively in the direction toward the discharge outlet C¹ thereof. As will be seen, the first convolution of the helix commences at the end of the trough remote from the outlet. It will be understood that the rearmost section of the conveyer should remove only its own quota of ash, *i. e.*, the ash lying immediately above

the same; the following section *i. e.*, that nearer the discharge outlet C¹ at the front of the furnace, should convey not only its own quota of ash but also that delivered by the rearward section thereto, and so on, so that the capacity of the conveyer will increase progressively from the bridge wall to the outlet. For crushing large pieces of clinker the plain parts of the conveyer C (*i. e.*, where the screw threads are omitted) may be formed with spikes C¹¹.

The conveyer C is made up of short lengths or screw-threaded sections strung on to a shaft of polygonal formation in cross section, one or more distance pieces or non-threaded sections being interposed to afford the interruptions above referred to. In this way adjustment of the relation of the various flights to that of the intervening non-threaded sections to meet varying requirements, can be readily effected.

What we claim is:—

1. In a furnace, the combination of a grate having inclined sides and an ash-receiving trough into which the inclined sides merge at their lower edges and which trough is provided at one end with a discharge outlet, of a rotary conveyer located in said trough and extending from the opposite extremity of said trough to said outlet, said conveyer comprising a shaft of non-circular formation in cross section, and screw threaded and interposed non-threaded sections strung on said shaft, the screw threads being of uniform depth and pitch, the screw-threaded sections being of unequal lengths, increasing progressively toward the discharge outlet, and the non-threaded sections being of unequal lengths, decreasing toward said outlet.

2. In a furnace, the combination of a grate having inclined sides and an ash-receiving trough into which the inclined sides merge at their lower edges and which trough is provided at one end with a discharge outlet, of a rotary conveyer located in said trough and extending from the opposite extremity of said trough to said outlet, said conveyer comprising a shaft of non-

2
circular formation in cross section, and
screw-threaded and interposed non-threaded
sections strung on said shaft, the screw
threads being of uniform depth and pitch,
5 the screw-threaded sections being of unequal
lengths, increasing progressively toward the
discharge outlet, the non-threaded sections
being of unequal lengths, decreasing toward
said outlet, and being provided with radial
10 breaking projections or spikes.

In testimony whereof we have signed our
names to this specification in the presence of
two subscribing witnesses.

WILLIAM ANDERSON.

JAMES MEIKLE.

CHARLES WILLIAM FULTON.
